(57) **CLAIM**

I claim the ornamental design for equipment storage tray, as shown and described.

DESCRIPTION

FIG. 1 is a perspective view taken from the upper right side of an equipment storage tray showing my new design; FIG. 2 is a top plan view thereof; FIG. 3 is a bottom plan view thereof; FIG. 4 is a front elevational view thereof; FIG. 5 is a rear elevational view thereof; FIG. 6 is a right side elevational view thereof; FIG. 7 is a left side elevational view thereof; and, FIG. 8 is a cross-sectional view thereof taken along line 8—8 of FIG. 2.
